UNITED STATES PATENT OFFICE

JOHN J. PUNKE, OF DETROIT, MICHIGAN, ASSIGNOR TO HUPP MOTOR CAR CORPORATION, OF DETROIT, MICHIGAN, A CORPORATION OF VIRGINIA

DESIGN FOR A COMBINED HORN BUTTON AND CONTROL LEVER

Application filed July 22, 1929. Serial No. 32,148. Term of patent 14 years.

To all whom it may concern:

Be it known that I, JOHN J. PUNKE, a citizen of the United States of America, residing at Detroit, in the county of Wayne and State of Michigan, have invented a certain new, original, and ornamental Design for Combined Horn Button and Control Lever, of which the following is a specification, reference being had therein to the accompanying drawing, forming a part thereof.

Figure 1 is a perspective view of a combined horn button and light control lever, showing my new design; and

Figure 2 is a front elevational view of the design shown in Figure 1.

I claim:

The ornamental design for a combined horn button and control lever substantially as shown.

JOHN J. PUNKE.
